UNITED STATES PATENT OFFICE.

JOSEPH BRUECK AND NORBERT SALTER, OF NEW YORK, N. Y.

FOUNTAIN COMB.

1,408,262.

Specification of Letters Patent. Patented Feb. 28, 1922.

Application filed August 15, 1921. Serial No. 492,607.

To all whom it may concern:

Be it known that we, JOSEPH BRUECK and NORBERT SALTER, both citizens of the United States, the former residing in the city of New York, county of Bronx, and State of New York, and the latter residing in the city of New York, county of New York, and State of New York, have invented certain new and useful Improvements in Fountain Combs, of which the following is a full, clear, and concise description.

Our invention relates to fountain combs, of a type suitable for use upon the hair of the head and upon beards, as well as upon wigs, false whiskers and the like for the purpose of subjecting the same to the action of dyes, medicines, oil, or water.

More particularly stated, our invention comprehends a comb suitable for use by hand and provided with means for containing and distributing a liquid, the parts being so constructed, proportioned and arranged that the operator, by using little or no more skill than would ordinarily be required in 20 combing the hair or the beard, can apply to the hair or the beard, and distribute evenly thereupon and throughout the mass thereof, a liquid which may be a dye, a medicine, a hair oil, a perfume, or even ordinary water.

Reference is made to the accompanying drawing forming a part of this specification, and in which like reference characters indicate parts throughout all of the figures.

Figure 1 is a side view, partly in elevation and partly as with parts broken away, of a representative form of our device.

Figure 2 is a section on the line 2—2 of Figure 1, looking in the direction indicated by the arrows.

Figure 3 is a fragmentary longitudinal section through the valve barrel and the portion of the handle immediately adjacent thereto.

Figure 4 is a view partly in side elevation and partly in section of the valve cylinder.

Figure 5 is a perspective of the distributing trough.

Figure 6 is a perspective of the comb frame.

Figure 7 is a perspective of one form of clamp for holding together certain parts of the device.

Figure 8 is a perspective of a form of clamp differing from that appearing in Figure 7, but used for the same general purpose.

A handle appears at 9, and is hollow.

This handle is provided with a neck 10, threaded externally, and detachably engaging this neck is a screw cap 11, threaded internally. By removing the screw cap 11 the handle 9 may be filled with a liquid, such as a liquid hair dye or a medicine in liquid form.

Mounted upon the handle 9 is a barrel 12, having the proximate form of a cylinder, and provided with a notch 13. The barrel 12 carries a pin 14, extending slightly from it in a direction parallel with its general axis, as may be understood from Figure 3. The handle 9 is provided with a partition 15, the latter being provided with a feed hole 16. The barrel 12 is provided with a slot 17 extending throughout nearly the entire length of the barrel, in a direction parallel with the longitudinal axis thereof.

Revolutely fitted into the barrel 12 is a valve cylinder 18 having a closed end portion 19, this end portion being provided with a feed hole 20. The valve cylinder is provided with a slot 21, extending in the general direction of the length of the valve cylinder and parallel with the longitudinal axis thereof. The slot 21 is so proportioned and arranged that it may be brought into or out of registry with the slot 17, by slightly turning the valve cylinder 18. This valve cylinder carries a stop pin 22, extending radially from it, and having a measure of angular play limited by the notch 13. The valve cylinder 18 is further provided with a thumb piece 23, whereby it may be turned within the limits permitted by the play of the pin 22 as limited by the notch 13. The operator by grasping the thumb piece 23 may turn the valve cylinder 18 within the limits permitted by movements of the pin 22 within the slot 13, and by so doing can bring the slot 21 into or out of registry with the slot 17, or into or out of partial registry therewith, as occasion may require.

A distributing trough 24, having generally the form indicated in Figure 5, is provided with a number of feed holes 25, and with end portions 26. The distributing trough 24 has in cross section a V-shape as indicated in Figure 2. The proportions of the distributing trough 24 and the barrel 12 are such that with the parts in position, as indicated in Figure 2, the upper edge portions of the distributing trough engage the barrel 12 and are located upon opposite sides thereof.

A comb frame is shown at 28, and has the form indicated in Figure 6. The comb frame 28 is at one of its ends provided with a hole 29, into which the pin 14 may be 5 thrust so as to enable the comb frame to be supported firmly upon the barrel 12, and braced relatively to this barrel. The comb frame 28 is provided with teeth 30, disposed parallel with each other as indicated in Figures 1 and 6, and each of substantially 10 V-shape.

A clamp 31, having the form indicated in Figure 6 is so arranged that it may be 15 slid telescopically over the upper edge of the comb frame and over the barrel 12, as may be understood from Figure 2.

A porous member 27, made preferably of 20 felt or cloth is fitted upon the outside of the distributing trough 24, and thus located within the comb frame, as may be understood from Figure 2.

In some instances, it may be preferable 25 to substitute a clamp of the form shown at 32, in Figure 8, for the clamp 31 shown in Figure 7. In such instances the clamp 32 occupies the position indicated for it by dotted lines in Figure 6.

In assembling the parts, the pin 14 is 30 extended through the hole 29, and the barrel 12 is brought between the walls of the frame comb 28. Previous to this, however, the porous member 27, of felt or cloth is fitted upon the outside of the distributing trough 24, and this trough, carrying the porous 35 member, is neatly fitted into the comb frame 28, as indicated in Figure 2. Therefore when the barrel 12 is brought fairly well down between the walls of the comb frame the barrel 12 presses tightly against the 40 edge portions of the distributing trough 24, and with the clamp 31 or the clamp 32 in position, the parts are held together quite firmly, as indicated in Figure 2. The valve cylinder 18 may be fitted into the barrel 45 12 either before or after the barrel 12 is fitted into position relatively to other parts. The valve cylinder 18 may at any time be turned by aid of the thumb piece 23, as 50 above described, so as to bring the slot 21 of the valve cylinder into or out of registry with the slot 17 of the barrel 12. Thus by an accurate adjustment of the valve cylinder 18 relatively to the barrel, the flow 55 of liquid from the valve cylinder 18 into the distributing trough 24 may be regulated. This means that the device may be so used as to control the quantity of liquid allowed to reach the porous member 27.

We will now explain the operation of our 60 device.

In order to fill the handle 9 with the liquid to be used, the operator first grasps the thumb piece 23 and turns the valve cylinder 18 into such position relatively to 65 the barrel 12 that the feed hole 20 is out

of registry with the feed hole 16. The entire device is now turned into a vertical position, so that the neck 10 is uppermost, the screw cap 11 being removed. The liquid to be used, for instance a liquid hair dye, 70 is next poured into the handle 9, through the neck 10, so as to fill the handle wholly or partially as desired. This done the screw cap is replaced. With the parts in the condition just described, the device may 75 be kept for any length of time without any of the liquid escaping, the feed holes 16 and 20 being out of registry. When our device is to be used, say for applying a dye to the hair, the operator grasps the thumb piece 80 23 and turns the valve cylinder 18 so as to bring the feed holes 16 and 20 and also the slots 17 and 21 into proper relation to allow the liquid to be fed into the distributing trough 24 at the proper rate of flow. This 85 done the operator, grasping the handle 9 as he would the handle of a brush or comb, so manipulates the device as to cause the teeth 30 to plough through the hair in much the same manner as would be the case with 90 an ordinary comb.

The porous member 27 becomes more or 95 less saturated with the liquid, and supplies the liquid in small quantities to the hair, as the porous member 27 is brought into contact therewith.

The distribution of the liquid throughout the mass of hair is practically uniform, so that by properly apportioning the quantity 100 of the liquid used, or the strength of the liquid, and by properly adjusting the position of the valve cylinder 18 as above described, the quantity of dye or other liquid material to be applied to the hair can be regulated within comparatively narrow 105 limits. Such being the case it is practicable to control the degree of coloring to be applied to the hair. A good way to do this is to use our device so as to render cumulative its action upon the hair. That is to 110 say, it is a good plan to apply the device for a short time in order to produce a slight coloration of the hair, and to use it for a longer time in order to render the coloration more intense. Thus with very little 115 practice any person can so use our device as to color or otherwise treat the hair in such manner that the effect is uniform throughout the entire mass of the hair.

While our device is peculiarly adapted for 120 use in dyeing the hair as above described, it may be used to advantage in coloring beards and mustaches, either natural or artificial, and in the preparation of wigs of different kinds. Our invention is equally well adapted 125 for applying medicines to the hair, beards or mustaches, as for instance in applying a so-called dandruff cure to the hair. It may be used for permeating the hair or the beard with liquids the purpose of which 130

is to destroy vermin therein. Last but not least it can be used for applying hair oils, perfumes and even plain water to either the hair or the beard. Thus our invention 5 can be appropriately designated as a fountain comb for general use.

We claim—

1. A fountain comb, comprising a hollow handle provided with means for holding a 10 liquid to be applied to the hair, a barrel carried by said handle, a valve member revolubly fitted into said barrel for the purpose of controlling the flow of said liquid from said barrel, a comb frame carried by 15 said barrel and provided with teeth, an absorbent member carried by said comb frame, and a distributing trough located within said comb frame and engaging said absorbent member in order to hold said absorbent member 20 in a predetermined position relative to said barrel, for the purpose of enabling said valve to discharge said liquid and thus to deliver the same to said absorbent member.

2. In a fountain comb the combination of 25 a comb frame provided with teeth, an absorbent member carried by said comb frame, a barrel carrying said comb frame and said absorbent member, a distributing trough carried by said barrel and engaging said absorbent member for the purpose of delivering 30 a liquid thereto, a valve carried by said valve for discharging said liquid from said barrel into said distributing trough, said valve being controllable at the will of the operator for the purpose of regulating the 35 flow of liquid from the barrel, and a hollow member connected with said barrel, and a hollow member connected with said barrel for the purpose of delivering thereinto a 40 liquid to be applied to the hair.

3. In a fountain comb the combination of 45 a comb frame, a flexible member carried thereby and made of absorbent material in order to hold by absorption a quantity of liquid to be distributed by aid of said comb frame, a distribution trough engaging said flexible member and provided with openings, a barrel engaging said distributing trough for the purpose of delivering thereinto quantities of said liquid, mechanism connected 50 with said trough and controllable at the will of the operator for regulating the delivery of the liquid from said barrel into said distributing trough, and a hollow handle connected with said barrel and adapted to serve 55 as a reservoir for holding a supply of said liquid and for delivering said liquid into said barrel.

4. A device of the character described, 60 comprising a hollow handle serving as a reservoir, a barrel carried by said handle and extending lengthwise therefrom, a partition provided with an opening for discharging a liquid from said handle into said barrel, a valve located within said barrel and

movable at the will of the operator for controlling the quantity of liquid thus discharged from said handle into said barrel, a comb frame carried by said barrel and provided with comb teeth, said comb frame being hollow and having in cross section a substantially V-shape, 70 an absorbent member carried by said comb frame and having generally the form of a web, and a distributing trough engaging said barrel and said absorbent member, said distributing trough having in cross section a substantially V-shape, 75 for the purpose of holding said absorbent member firmly within said comb frame and of conferring upon said absorbent member a substantially V-shape in cross section.

5. In a device of the character described, the combination of a comb frame provided with teeth, said comb frame being hollow, a 80 porous member located within said comb frame for the purpose of holding by absorption a liquid to be distributed by aid of said teeth, and a distributing trough located within said comb frame and engaging said porous member for the double purpose of holding said porous member in a predetermined position relative to said teeth and supplying the liquid to said porous member.

6. A device of the character described 95 comprising a hollow comb frame provided with teeth and with an opening, a barrel extending through said comb frame and provided with a projecting member extending through said opening for the purpose of holding said barrel and said comb frame together, a clamping member for further holding said barrel and said comb frame together, an absorbent material disposed within said comb frame for the purpose of receiving a liquid from said barrel and delivering the same through said comb frame to a person's hair or the like, and means for delivering a liquid into said barrel.

7. A device of the character described 110 comprising a hollow member serving the double purpose of a reservoir and a handle, a barrel carried by said hollow member and provided with an inlet opening and with a discharge slot, a valve member mounted 115 within said hollow member and likewise provided with an inlet opening and a discharge slot, said valve member being provided with means whereby it may be turned relatively to said barrel for the purpose of bringing the inlet opening of the valve member into and out of registry with the inlet opening of the barrel and of bringing the slot of the valve member into and out of registry with the slot of the barrel, and a comb frame connected with said barrel for the purpose of holding and distributing an absorbent material.

8. In a device of the character described 120 the combination of a hollow member serving the double purpose of a reservoir and a han- 130

dle, a barrel of substantially cylindrical form carried by said hollow member and extending lengthwise therefrom, said barrel being provided with an inlet opening between it and said hollow member and further provided with a discharge slot, a valve cylinder fitted into said barrel and having a limited revolvable movement relatively thereto, said

valve cylinder having an inlet opening mating the inlet opening of said barrel and having a discharge slot mating the discharge slot of said barrel, and a comb frame carried by said barrel for distributing a liquid delivered thereinto from said barrel. 10

JOSEPH BRUECK.
NORBERT SALTER.
